RAILWAY TRAFFIC CONTROLLING APPARATUS

Earl M. Allen, Swissvale, Pa., assignor to The Union Switch & Signal Company, Swissvale, Pa., a corporation of Pennsylvania

Application January 30, 1943, Serial No. 474,069

5 Claims. (Cl. 246—160)

My invention relates to railway traffic controlling apparatus, and particularly to apparatus of the type involving locking means for at times preventing operation of a railway track switch or a signal in an interlocking system. More specifically, my invention relates to the release of approach locking in a railway interlocking system.

The apparatus of my present invention is an improvement over that disclosed in my copending application, Serial No. 465,215, filed November 11, 1942, for Railway traffic controlling apparatus.

In order to reduce the number of line wires required in a railway interlocking control system, it is desirable, in the control of an approach locking relay associated with a given signal, to use, as an approach relay, a traffic responsive signal relay which serves for controlling an opposing signal. If a distant signal for the given signal is manually controlled, the signal control relay for the opposing signal, as usually controlled, will be deenergized when the distant signal is controlled to indicate caution or proceed. Therefore, if while the given signal and the distant signal are indicating caution or proceed, a leverman restores the given signal to its stop indication without the distant signal being also controlled to indicate stop, the signal control relay for the opposing signal will remain deenergized, and hence an approach locking release circuit controlled by this signal relay for energizing the approach locking relay for the given signal will be open. The approach locking relay can then become energized only upon the lapse of a time interval determined by time releasing means. This is an unnecessary delay in the release of the approach locking if there is no train approaching the distant signal, and therefore reduces the flexibility of the system.

One feature of my invention is the provision of means for momentarily energizing the signal control relay for the opposing signal if the distant signal is controlled to change from displaying a proceed indication to displaying the caution indication when the given signal is returned to its stop indication. The approach locking relay thus becomes energized by a pick-up circuit, and is retained in the energized condition by its stick circuit after the signal control relay for the opposing signal becomes deenergized following its momentary energization.

I shall describe one form of apparatus embodying my invention, and shall then point out the novel features thereof in claims.

The accompanying drawings, Figs. 1a and 1b, when placed end to end, with Fig. 1a on the left, constitute a diagrammatic view showing one form of apparatus embodying my invention. Fig. 1c comprises a table of relay controls which are not shown, but which are similar to corresponding relay controls which are shown in Figs. 1a and 1b.

Referring to the drawings, the reference characters 5 and 5a designate the rails of a stretch 10 of railway track over which traffic movements may be made in either direction. Adjacent the left-hand end of this stretch of track, as shown in the drawings, which I shall assume is the west end, is a switch 1. Adjacent the opposite or east end of the stretch of track is a second switch 3.

Rails 5 and 5a are divided by insulated joints 6 to form sections 12T, A2T, 1T, A3T, 3T, and A4T. Each of these track sections is provided with a track circuit including a suitable source of 20 current, such as a battery 1, connected across the rails adjacent one end of the section, and a track relay, designated by a reference character which is the same as the reference character for the associated section except that it includes the letter R instead of the letter T, connected across the rails adjacent the opposite end of the section.

An approach relay AR is controlled by relays 12R and A2R.

Eastbound traffic movements over the stretch 30 of track are governed by signals 12, R2, RA4 and RB4. Westbound traffic movements over the stretch of track are governed by signals L4, LA2, and LB2. Arm A of signal R2, which may also be designated signal RA2, governs traffic movements over switch 1 in the normal position, whereas arm B of this signal, or signal RB2, governs traffic movements over switch 1 in the reverse position. Arms A and B of signal L4 similarly govern traffic movements over switch 40 3 in the normal and reverse positions, respectively. Signal RA2 serves as a distant signal for signal RA4 and since, as shown in the drawings, the distance between signals RA2 and RA4 is less than braking distance, signal 12 serves as a second distant signal for signal RA4. The signals shown in the drawings may be of any suitable type such, for example, as color light or search-light signals.

The contacts operated by the various relays 50 and other control devices are identified by numbers each such number having a distinguishing prefix from which it is separated by a dash when the associated contact is shown apart from the relay or other device by which it is operated. 55. The prefix for each of these contact numbers

comprises the reference character for the relay or other device by which the associated contact is operated. For example, contact 2RA-70, shown in the circuit for relay 2PC in the upper right-hand portion of Fig. 1a, is identified by the number 70 which is separated by a dash from the prefix 2RA which is the reference character for relay 2RA by which this contact is operated.

Track switch 1 is operated between its normal and reverse positions by a suitable mechanism designated by the reference character 1M. This mechanism is in turn controlled by a polarized switch control relay 1W.

Relay 1W is controlled by remotely controlled switch relays 1NS and 1RS and by a switch locking relay 1L.

Relay 1L is controlled by approach locking stick relays L2L and R2L, and by track relay 1R.

Relays L2L and R2L may be controlled similarly to relay R4L shown in Fig. 1b.

A switch contact 8 is operated in conjunction with switch 1 so that this contact is closed in its normal or its reverse position according as switch 1 is in the normal or the reverse position, respectively. Contact 8, when in its normal position, completes a circuit for energizing a normal switch indication relay 1NP, and when in its reverse position, completes a circuit for energizing a reverse switch indication relay 1RP.

Signals LA2, LB2, RA2 and RB2 are controlled by home control relays 2LA, 2LB, 2RA and 2RB, respectively. These home control relays are in turn controlled by route relays L2R and R2R, and also by the switch indication relays, switch locking relay, and approach locking relays.

Route relays L2R and R2R are controlled by remote controlled signal relays L2S and R2S, by polarized traffic responsive signal relays L2D and R2D, and also by remote controlled switch relays 1NS and 1RS, by switch indication relays 1NP and 1RP, by approach locking stick relays L2L and R2L, and by track relay 1R.

Traffic responsive signal relay L4D is controlled by track relays 1R and A3R for track sections 1T and A3T between signal RA4 and its distant signal RA2, if approach locking relay R2L associated with signals R2 is energized. Another circuit for energizing relay L4D, controlled by relays 2PC and 2PP, is momentarily closed when signal RA2 is controlled to indicate caution or stop after it has been controlled to indicate proceed, if there is no train in the approach sections 12T and A2T for signal RA2 so that relay AR is energized. The polarity of the current by which relay L4D is energized is determined by pole changing contacts of relay 2LA. Relay R2D for traffic movements in the opposite direction is controlled similarly to relay L4D.

Proceed signal control repeater relay 2PC is controlled by relays 2RA and R2D so as to be energized only if signal RA2 is controlled to indicate proceed. Slow release signal control repeater relay 2PP is controlled by relay 2PC so as to be energized only if relay 2PC is energized.

Route relay R4R, shown in Fig. 1b, is controlled similarly to relay L2R shown in Fig. 1a, and home control relays 4RA and 4RB for signals RA4 and RB4 are controlled similarly to relays 2LA and 2LB, also shown in Fig. 1a.

Approach locking stick relay R4L is provided with a normally energized pick-up circuit including a front contact of relay L4D, as well as with a long time release circuit for high speed traffic movements, and a short time release circuit for low speed traffic movements over switch 3 in the

reverse position. The time release circuits for relay R4L are controlled by time element devices 4BE and 4E, by slow release auxiliary stick relays 4BS and 4ES, and by an auxiliary stick relay 4Z.

Switch operating mechanism 3M for switch 3 is controlled by relay R4L through a switch locking relay which controls a switch control relay similarly to the manner shown by which switch operating mechanism 1M is controlled by relay L2L in Fig. 1a.

Switch indication relays 3NP and 3RP for switch 3 are controlled similarly to relays 1NP and 1RP for switch 1.

Having described, in general, the arrangement and control of the apparatus shown by the accompanying drawings, I shall now describe, in detail, its operation.

As shown by the drawings, all parts of the apparatus are in the normal condition, that is, switches 1 and 3 are in their normal positions; signal 12 is indicating caution, and all other signals are indicating stop; normal operating circuits are arranged for switch mechanisms 1M and 3M as shown for mechanism 1M; relays AR, 1NS, 1NP, 1L, 4Z, and R4L are energized; relay 1W is energized by current of normal polarity; relays R2D and L4D are energized by current of reverse polarity; and relays R2S, L2S, 1RS, 1RP, R2R, L2R, 2RA, 2RB, 2LA, 2LB, 2PC, 2PP, 4BS, 4ES, and time element devices 4BE and 4E are deenergized.

The normal operating circuit for mechanism 1M passes from terminal B of a suitable source of current, through contact 1W-9 and contact 1W-10 in its normal position, and mechanism 1M to terminal O of the same source of current. Relay 1NP is energized by its circuit passing from terminal B, through switch contact 8 in the normal position, and the winding of relay 1NP to terminal O.

Approach relay AR is energized by its circuit passing from terminal B, through contacts 13 and 14 of relays A2R and 12R respectively, and the winding of relay AR to terminal O.

Relay 1L is energized by a circuit passing from terminal B, through the front point of contact 15 of relay L2L, contacts R2L-16 and 1R-17, and the winding of relay 1L to terminal O.

Relay 1W is energized in the normal direction by a circuit passing from terminal B, through the front point of contact 1L-18, front point of contact 1NS-19, winding of relay 1W, and the back point of contact 1RS-20 to terminal O.

Relay L4D is energized by current of reverse polarity in a circuit passing from terminal B, through the back point of contact 2LA-21, contact A3R-29, winding of relay L4D, contacts A3R-28, 1R-26, and R2L-25, and the back point of contact 2LA-30 to terminal O. Relay R2D is similarly energized by current of reverse polarity in its circuit passing from terminal B, through the back point of contact 4RA-31, contact A3R-29, winding of relay R2D, contacts A3R-38, 3R-36, and L4L-35, and the back point of contact 4RA-39 to terminal O.

A pick-up circuit is closed for energizing relay 4Z, passing from terminal B, through contacts 40, 41 and 42 of relay R4R, 4RA, and 4RB, respectively, contacts 4E-43 and 4BE-44, back point of contact 4ES-45, contact 4BS-46, and the winding of relay 4Z to terminal O. A stick circuit is also closed for relay 4Z which follows the pick-up circuit as far as contact 42 of relay 4RB, and then passes through contact 41 of relay 4Z, and the winding of relay 4Z to terminal O.

A pick-up circuit is closed for energizing relay R4L, passing from terminal B through contacts 40, 41 and 42 of relays R4R, 4RA, and 4RB, respectively; contact 43 of relay 3NP; contact L4D—45; and the winding of relay R4L to terminal O. A stick circuit is also closed for relay R4L, following the pick-up circuit for this relay as far as contact 42 of relay 4RB, and then passing through the front point of contact 54 of relay R4L, and the winding of relay R4L to terminal O.

I shall assume that a leverman effects energization of relay R2S to clear signal RA2. Relay R2R then becomes energized by its circuit passing from terminal B, through contact 55 of relay L2R, contact L2L—56, back point of contact 57 of relay L2S; contact 58 of relay 1R, contact 59 of relay 1NP; contact 60 of relay 1NS, front point of contact 61 of relay R2S, contact R2D—62, and the winding of relay R2R to terminal O. Relay R2R, upon becoming energized, deenergizes relay R2L similarly to the manner in which relay R4R would deenergize relay R4L upon becoming energized.

Relay R2L, upon becoming deenergized, opens the circuit traced for relay 1L at its contact R2L—16, causing relay 1L to also become deenergized.

Relay 1L, upon becoming deenergized, opens its contact 1E—18 at the front point, thereby deenergizing relay 1W.

When relay 1W becomes deenergized, its contact 1W—9 becomes opened in the circuit previously traced for mechanism 1M.

With relays 1L and R2L deenergized, and with relay R2R energized, relay 2RA becomes energized by a circuit passing from terminal B, through the back point of contact 1L—18, contact 63 of relay R2L, back point of contact L2R—64, contact 1NP—65, front point of contact R2R—66, contact 67 of relay 2RB, and the winding of relay 2RA to terminal O.

I shall also assume that signal RA4 is similarly cleared. Relay R4L therefore becomes deenergized on account of contact 40 of relay R4R becoming opened. Relay 4Z is also deenergized on account of contact 40 of relay R4R becoming opened. Relay 4RA becomes energized similarly to the manner in which relay 2RA becomes energized as previously described.

With relay 4RA energized, relay R2D becomes energized by current of normal polarity in a circuit which is the same as the circuit previously traced except including the front points of contacts 4RA—31 and 4RA—39 instead of the back points of these contacts.

With relay 2RA energized, and with relay R2D energized by current of normal polarity, signal RA7 is operated to the proceed position by a circuit passing from terminal B, through contacts 2RA—68 and R2D—69, and the mechanism of signal RA2 to terminal O.

At the same time, relay 2PC becomes energized by a circuit passing from terminal B, through contacts 2RA—70 and R2D—71, and the winding of relay 2PC to terminal O. Relay 2PP then becomes energized by its circuit passing from terminal B, through the front point of contact 72 of relay 2PC, and the winding of relay 2PP to terminal O.

I shall further assume that after a train arrives on section 12T, the leverman decides to restore signal RA4 to the stop indication, but does not restore signal RA2 to the stop indication. With relay 4RA therefore becoming deenergized, the circuit traced for relay R2D through the back

points of contacts 4RA—31 and 4RA—39 again becomes closed, causing relay R2D to become energized in the reverse direction and therefore open its contact R2D—69 in the proceed control circuit previously traced for signal RA2.

The arm of signal RA2 is now retained in the caution position by its circuit passing from terminal B, through contact 2RA—68, and the mechanism of signal RA2 to terminal O. Relay L4D has previously been deenergized when signal RA2 was operated to the proceed position, because of contact R2L—25 becoming open due to the deenergization of relay R2L.

The pick-up circuit previously traced for relay 4Z now becomes closed, causing relay 4Z to become energized and complete its stick circuit previously traced.

On account of relay L4D being deenergized, the pick-up circuit previously traced for relay R4L is now open at contact L4D—49.

With relay R4L deenergized, a circuit is now completed for energizing time element device 4BE, passing from terminal B, through contacts 40, 41 and 42 of relays R4R, 4RA and 4RB, respectively, back point of contact 54 of relay R4L, contact 4Z—73, back point of contact 74 of relay 4BS, and time element device 4BE to terminal O. Upon the lapse of a measured period of time, contact 15 of time element device 4BE will close, thereby completing a pick-up circuit for relay 4BS which is the same as the energizing circuit previously traced for device 4BE as far as contact 4Z—73, and then passes through contact 15 of device 4BE, and the winding of relay 4BS to terminal O.

Relay 4BS, upon becoming energized, opens the circuit for device 4BE at the back point of contact 74, and completes its own stick circuit through the front point of contact 74.

A circuit is now closed for energizing time element device 4E, which follows the path previously traced for the energizing circuit for device 4BE as far as contact 4Z—73 and then first passes through contact 15 of device 4BE, and afterwards passes through the front point of contact 74 of relay 4BS, the back point of contact 76 of relay 4ES, and time element device 4E, to terminal O.

Time element device 4E, upon remaining energized for a measured period of time, completes a circuit for energizing relay 4ES, which is the same as the circuit for energizing device 4E as far as the front point of contact 74 of relay 4BS, and then passes through contact 77 of device 4E, and the winding of relay 4ES to terminal O. Relay 4ES, upon becoming energized, opens the circuit traced for device 4E at the back point of contact 76, and then completes its own stick circuit at the front point of contact 76.

As soon as the back contacts of devices 4E and 4BE have closed after these devices have become deenergized, a second pick-up circuit will become closed for energizing relay R4L, passing from terminal B, through contacts 40, 41 and 42 of relays R4R, 4RA and 4RB, respectively, contacts 4E—43 and 4BE—44, front point of contact 4ES—45, contact 4BS—53, and the winding of relay R4L to terminal O.

I shall next assume that all parts of the apparatus are again returned to the normal condition, and that the leverman then clears signal RA4 but does not clear signal RA2 which, therefore, continues to indicate stop. I shall further assume that the leverman returns signal RA4 to the stop indication while track sections 1T and

A3T are still unoccupied. Relay L4D is now energized in the reverse direction by its circuit first traced.

As soon as signal RA4 is returned to the stop position, relay 4Z will become energized by its pick-up circuit previously traced. With relay L4D energized, relay R4L will become energized by its pick-up circuit first traced as soon as signal RA4 is returned to the stop indication.

I shall now assume that all parts of the apparatus are again returned to the normal condition, and that the leverman clears both signals RA4 and RA2 as previously described, but that before a train enters section 12T, he returns signal RA4 to the stop indication, but does not return signal RA2 to the stop indication. Relay 4RA will therefore be deenergized, causing relay R2D to again be energized in the reverse direction by its circuit first traced.

Relay R2D, upon becoming energized in the reverse direction, opens its contact R2D-71 in the circuit traced for relay 2PC, causing this relay to become deenergized and thereby open the circuit previously traced for relay 2PP.

The winding of relay 2PP is then connected in a shunt circuit with both of its terminals connected to terminal O of the source of current through the back point of contact 72 of relay 2PC. Relay 2PP will therefore be slow to release. The front contact of relay 2PP will therefore remain closed for a brief period of time after the back contacts of relay 2PC have closed.

A circuit is therefore momentarily closed for energizing relay L4D, passing from terminal B, through the back point of contact 2LA-21, contact A3R-29, winding of relay L4D, contacts A3R-28, 1R-26, AR-24, 2PP-23, 2PC-22, and the back point of contact 2LA-30 to terminal O. With relay L4D momentarily energized, relay R4L will therefore become energized by its pick-up circuit first traced, and will then remain energized by its stick circuit.

From the foregoing description and the accompanying drawings, it follows that in apparatus embodying my invention in the control of an approach locking relay associated with a given signal such, for example, as relay R4L associated with signal RA4 shown in the drawings, I have provided means for using, as an approach relay, a traffic responsive signal relay for an opposing signal such, for example, as relay L4D for signal LA4. By the arrangement which I have provided, the flexibility in the release of approach locking is the full equivalent of that which is provided if a separate approach relay with separate line wires is used. My invention, therefore, provides equivalent results with a lesser amount of control apparatus and conductor material.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In release means for energizing a locking stick relay associated with a signal adjacent a given stretch of track for governing traffic movements in a given direction over said given stretch of track in a railway interlocking system, including a distant signal for said first signal responsive to manually controllable control means, including a third signal in said given direction beyond said first signal for governing traffic move-

ments in the opposite direction over said given stretch of track, including a normally energized signal relay for controlling said third signal responsive to traffic conditions and also controlled by the control means for said distant signal so that said signal relay is deenergized if said distant signal is controlled to display an indication other than stop, the combination comprising, a circuit responsive to control means for said distant signal for momentarily energizing said signal relay if said distant signal is controlled to change from displaying the proceed indication to displaying the caution indication, and means including a front contact of said signal relay for energizing said locking stick relay.

2. In release means for energizing a locking stick relay associated with a signal adjacent a given stretch of track for governing traffic movements in a given direction over said given stretch of track in a railway interlocking system, including a distant signal for said first signal, including a third signal in said given direction beyond said first signal for governing traffic movements in the opposite direction over said given stretch of track, including a normally energized signal relay for controlling said third signal responsive to traffic conditions if said distant signal is controlled to indicate stop, including a repeater relay which is energized only if said distant signal is controlled to display the proceed indication, the combination comprising, a slow release relay, a circuit controlled by a front contact of said repeater relay for energizing said slow release relay, a circuit controlled by a back contact of said repeater relay in series with a front contact of said slow release relay for momentarily energizing said signal relay, and a pick-up and a stick circuit for said locking stick relay each controlled by a contact which is closed if said first signal is controlled to indicate stop and the pick-up circuit also controlled by a front contact of said signal relay.

3. In a railway interlocking system having a locking stick relay associated with a signal adjacent a given stretch of track for governing traffic movements in a given direction over said given stretch of track, including a distant signal for said first signal, including a third signal in said given direction beyond said first signal for governing traffic movements in the opposite direction over said given stretch of track, including a signal relay for controlling said third signal responsive to traffic conditions between said distant and third signals if said distant signal is controlled to indicate stop, the combination comprising, a circuit responsive to control means for said distant signal for energizing said signal relay if said distant signal is controlled to display the caution indication after displaying the proceed indication, and a pick-up circuit for said locking stick relay controlled by a front contact of said signal relay.

4. In a railway interlocking system having a locking stick relay associated with a signal adjacent a given stretch of track for governing traffic movements in a given direction over said given stretch of track, including a distant signal for said first signal, including a third signal in said given direction beyond said first signal for governing traffic movements in the opposite direction over said given stretch of track, including a signal relay for controlling said third signal responsive to traffic conditions between said distant and third signals if said distant signal is controlled to indicate stop, the combination comprising,

prising, a circuit responsive to control means for said distant signal for momentarily energizing said signal relay if said distant signal is controlled to indicate caution after indicating proceed and if an approach track section in the rear of said distant signal is unoccupied, and a pick-up circuit for said locking stick relay controlled by a front contact of said signal relay.

5. In a railway interlocking system having a locking stick relay associated with a signal adjacent a given stretch of track for governing traffic movements in a given direction over said given stretch of track, including a distant signal for said first signal, including a third signal in said given direction beyond said first signal for 15

governing traffic movements in the opposite direction over said given stretch of track, including a signal relay for controlling said third signal responsive to traffic conditions in advance of said third signal if said distant signal is controlled to indicate stop, the combination comprising, a circuit responsive to control means for said distant signal for momentarily energizing said signal relay if said distant signal is controlled to indicate caution after indicating proceed, and means controlled by a front contact of said signal relay for energizing said locking stick relay.

EARL M. ALLEN.
